(57) **CLAIM**

The ornamental design for a switch handle for circuit breakers, as shown and described.

DESCRIPTION

FIG. 1 is a front, side perspective view of a the switch handle for circuit breakers showing our design;

FIG. 2 is rear, side perspective view thereof;

FIG. 3 is a top view thereof (the bottom view is disclaimed);

FIG. 4 is a side view thereof;

FIG. 5 is a side view opposite that shown in FIG. 4;

FIG. 6 is a rear view taken at 90 degrees from the view shown in FIG. 5;

FIG. 7 is a front view opposite that shown in FIG. 6;

FIG. 8 is a front, side perspective view of the switch handle for circuit breakers of FIG. 1 shown in an exemplary environmental view on a respective door of a unit of a circuit breaker;

FIG. 9 is a front, side perspective view of the switch handle for circuit breakers of FIG. 1 shown in another exemplary environmental view on a door of a unit of a circuit breaker;

FIG. 10 is a front, side perspective view of the switch handle for circuit breakers shown in FIGS. 1-9, illustrated in an extended lever configuration;

FIG. 11 is a rear, side perspective view thereof;

FIG. 12 is a top view thereof (the bottom view is disclaimed);

FIG. 13 is a side view thereof;

FIG. 14 is a side view opposite that shown in FIG. 13;

(Continued)

FIG. 15 is a rear view taken at 90 degrees from the view shown in FIG. 14;

FIG. 16 is a front view opposite that shown in FIG. 15; FIG. 17 is a front, side perspective view of the switch handle for circuit breakers of FIG. 10, with the extended lever shown in an exemplary environmental view on a respective door of a unit of a circuit breaker in an exemplary extended lever orientation; and,

FIG. 18 is a front, side perspective view of the switch handle for circuit breakers of FIG. 10, with the extended lever shown in another exemplary environmental view on a door of a unit of a circuit breaker.

The broken lines shown herein are for illustrative purposes only and form no part of the claimed design.
